UNITED STATES PATENT OFFICE

2,350,616

SUPERCHARGER

Howard A. Johnson, Melrose, Mass., assignor to
General Electric Company, a corporation of
New York

Application December 2, 1942, Serial No. 467,569

10 Claims. (Cl. 230—127)

The present invention relates to compressors and especially to compressors for turbosuperchargers although it is not limited thereto necessarily. The invention has to do particularly with the stationary part of the compressor, i. e., the casing and diffuser structure.

Compressors of turbosuperchargers are subjected to severe operating conditions due to the high temperatures involved, the high speeds of the rotating parts, and the differences in temperature existing between contiguous parts. Temperatures may be of the order of 400 degrees F., speeds may be of the order of 25,000 R. P. M. and the temperatures of contiguous parts may differ by as much as 400 degrees F. In addition, relatively moving parts must run with close clearances, clearances of the order of .040 to .050 inch, to obtain good efficiencies. This requires that the stationary structure of the compressor must be rigid and well supported so as to maintain the desired clearances and avoid rubbing of relatively moving parts. At the same time, the compressor must be relatively light in weight, weight being an important factor in apparatus for use on aircraft.

One object of my invention is to provide an improved construction and arrangement of the stationary structure of a centrifugal compressor which is light in weight, capable of being manufactured in quantities at low cost and which will fulfill the exacting operating requirements met with in connection with turbosuperchargers.

A further object of my invention is to provide an improved construction and arrangement whereby the stationary structure can be quickly and easily assembled on and removed from the turbosupercharger as a unit.

Other objects and advantages of my invention will be pointed out hereinafter.

For a consideration of what I believe to be novel and my invention, attention is directed to the following specification and the claims appended thereto.

In the drawings, Fig. 1 is a sectional view of a centrifugal compressor which forms a part of a turbosupercharger and which has a stationary structure embodying my invention; Fig. 2 is an exploded view showing in perspective the several parts of which the compressor casing is composed; Fig. 2^a is a perspective view from a different angle of certain parts shown in Fig. 2; Fig. 3 is a perspective view of a diffuser vane, and Fig. 4 is a detail sectional view of certain parts.

Referring to the drawings, 1 indicates a bearing housing which supports a suitable bearing in which is mounted the turbosupercharger shaft 2,

5 mounted on one end of shaft 2 is the compressor impeller 3. On the other end of shaft 2 is mounted the bucket wheel (not shown) of the turbosupercharger, as is known. The compressor casing is supported on arms 4 formed integral with bearing housing 1, four arms being indicated in the present instance. At 5 are webs fixed to the arms and to the bearing housing for reinforcing and strengthening the arms.

10 The stationary part of the compressor comprises walls forming an inlet 6, a diffuser 7, an annular discharge scroll 8 and a discharge conduit 9. This stationary structure is attached to arms 4 by tie bolts 10, forming a support for the bearing and the turbine, and it is itself adapted to be attached to a suitable support by ears 11.

15 Referring now particularly to Figs. 2, 2^a and 3, the stationary structure of the compressor comprises a rear scroll section 12, a rear cone section 13, diffuser vanes 14, a diffuser vane plate 15, a front cone section 16 and a front scroll section 17. The rear and front scroll sections 12 and 17 are provided with flanges 18 and 19, respectively, which are suitably welded together, and their walls are shaped as shown clearly in the drawings to define the annular discharge scroll 8 and the discharge conduit 9.

20 Rear cone section 13 comprises an axially extending wall 20 which defines inlet 6, a curved impeller wall 20^a adjacent to which the open side of impeller 3 runs, and a radially extending wall 21 which forms a side wall of the diffuser. Rear scroll section 12 is provided with an annular flange 22 which is suitably welded to wall 21 as is best shown in Figs. 1 and 4.

25 The diffuser vanes each comprise a curved partition wall 23 provided with side flanges 24 and 25 (see Fig. 3). The side flanges are notched and shaped to fit together as is shown in Fig. 2 and when thus assembled define curved diffuser passages for the flow of fluid. Flanges 24 are suitably welded to wall 21. Flanges 25 are suitably welded to diffuser plate 15 which is saw tooth shaped as shown in Fig. 2 so that in contour it corresponds with the side contour of assembled flanges 25. Diffuser plate 15 is provided with an axially extending flange 26 which is suitably welded to the outer surfaces of front cone section 16. Front cone section 16 has a radially inwardly extending flange 27 and an axially extending flange 28 which is suitably welded to an axially extending flange 29 on front scroll section 17. Welded to the walls which define inlet 6 and outlet 9 are suitable flanges 30 and 31, respectively, provided with openings to receive bolts for attachment to pipe lines.

Mounting ears 11 are suitably welded to flanges 18, 19 and scroll section 17 and they are provided with reinforcing webs 32 which are welded to section 17, the webs extending radially across section 17 down to flange 29. Four mounting ears 11 are shown. They are provided with openings 33 to receive bolts for mounting the turbosupercharger on a support. Also they are provided with openings 34 to receive the ends of the rods 35 which support a cooling air baffle plate 36. Attached to scroll section 17 are additional ears 37, three in the present instance, located between ears 11 for additional tie rods 35. Ears 37 are reinforced by webs 38 which are welded to the ears and to scroll section 17. Welded to flanges 28, 29 in line with the inner ends of webs 32 are spaced lugs 39 in which the ends of the bolts 10 are threaded. At 40 are a number of reinforcing rods which at one end are welded to diffuser vane plate 15 and at the other end to scroll section 17, being in line with webs 32. In Figs. 2 and 2^a, 41 indicates the openings in scroll section 17 and webs 32 through which the ends of rods extend.

The opening 42 defined by flange 27 on front cone section 16 is of a diameter larger than the diameter of impeller 3 and such opening is closed by a plate 43 supported by the bolts 10 through the intermediary of webs 44 which at one end are welded to plate 43 and at the other end are located between collars 46 on the bolts 10 and arms 4, as best shown in Fig. 4. Between flange 27 and the periphery of plate 43 is a suitable packing 45.

One advantage of our invention is the ease and accuracy with which the structure may be assembled. The several parts 12 to 17, inclusive, may be made from sheet steel. All parts are so shaped that they can be readily formed as stampings. In assembling the construction, the rear scroll section 12 and the rear cone section 13 may be correctly positioned relatively to each other and seam welded together, after which the several diffuser vanes 14 may be spot welded to flange 21. Next, the diffuser vane plate 15 and the front cone section 16 may be accurately positioned relatively to each other and welded together by seam welding, for example, and reinforcing rods 40 welded to the diffuser vane plate. This assembly may then be attached to the assembly comprising rear scroll section 12, rear cone section 13 and the diffuser vanes 14 by spot welding flanges 25 to vane plate 15. There is now left only the front scroll section 17 and it may be readily positioned on the assembled construction, flange 19 being seam welded to flange 18 and the ends of reinforcing rods 40 which now project through openings 41 welded on the outside. Following this, the lugs 11, 37 and 39 and the reinforcing webs 32 and 38 may be welded into place.

The structure as a whole may be readily mounted on supporting arms 4 by assembling it over the impeller wheel and positioning the tie bolts 10. Tie bolts 10 may be attached to lugs 39 before the casing is positioned on the turbosupercharger. It is then merely necessary to pass the tie bolts through the openings in arms 4 and position the nuts on the ends of the tie bolts. To dismantle the construction, it is necessary merely to remove the nuts from bolts 10 and tie rods 35 whereupon the casing can be removed axially.

It will be noted that the rear cone section 13, diffuser vane plate 15 and the front cone section 16 are made from heavier metal than are the

front and rear scroll sections 12 and 17. These sections 13, 15 and 16, when assembled with the diffuser vanes 14 and the lugs 39, form a rigid structure of heavier metal. In the operation of the compressor, it is important to maintain a close clearance between the inner surface of wall 20^a and the adjacent edges of the impeller blades. This clearance is defined by the engagement of lugs 39 with the ends of supporting arms 4. Accordingly, the clearance may be adjusted by means of shims located on the bolts 10 between lugs 39 and arms 4. Of the assembled casing structure, only the outer surfaces of lugs 39 require machining. These are machined accurately with respect to the inner surface of wall 20^a of the rear cone section so as to make this distance accurate. In other words, the surface of lugs 39 is machined accurately with respect to the inner surface of wall 20^a to a dimension such that when the casing is assembled there will obtain a correct clearance between wall 20^a and the edges of the impeller vanes. This is the only critical dimension requiring close tolerance. Since there is only one dimension to be machined accurately, there can be no accumulation of tolerances as may be the case where there are several surfaces which are assembled relatively to each other, each with its own tolerance. This makes for ease of manufacture and accuracy in the finished product.

In use, the turbosupercharger as a whole is supported by ears 33. Ears 33 are reinforced by webs 32 in line with the inner ends of which are the lugs 39, all these elements being welded together. Thus, viewed from one aspect, ears 33, webs 32 and lugs 39 form in substance rigid supporting arms for the turbosupercharger as a whole, the arms being connected together or reinforced by front scroll section 17. Accordingly, when ears 33 are bolted to a main support, the bearing and bearing housing are rigidly fixed in position to carry the overhung compressor impeller and the overhung turbine wheel.

In accordance with the provisions of the patent statutes, I have described the principle of operation of my invention, together with the apparatus which I now consider to represent the best embodiment thereof, but I desire to have it understood that the apparatus shown is only illustrative and the invention may be carried out by other means.

What I claim as new and desire to secure by Letters Patent of the United States is:

1. A fabricated, welded compressor casing structure comprising walls united by fused metal to form a unitary rigid structure which provides a diffuser, a wall adjacent to which the compressor impeller runs and spaced mounting lugs having supporting surfaces accurately spaced in an axial direction from the inner surface of said wall, and walls which form a discharge scroll attached to said rigid structure.

2. In a centrifugal compressor having a rotating impeller overhung on a shaft end, a fabricated unitary rigid casing structure for the compressor comprising spaced walls which define a diffuser surrounding the impeller, one of said walls having an extension which forms the portion of the casing adjacent which the impeller runs and another of said walls having an axially extending portion having mounting lugs attached thereto, said mounting lugs having mounting surfaces accurately dimensioned with respect to said wall extension, and walls which

form a discharge scroll attached to said first named walls.

3. A fabricated welded compressor casing structure comprising a cone-shaped section which defines an inlet, an impeller vane wall, and a diffuser side wall, a second diffuser side wall, diffuser vanes welded between said diffuser side walls, a second cone-shaped section welded to said second diffuser side wall, attaching lugs welded to said second cone-shaped section, said lugs having finished surfaces dimensioned with respect to said impeller vane wall, and front and rear scroll sections attached to said cone-sections.

4. In a supercharger, the combination with a bearing housing having spaced supporting arms, a shaft, and an impeller fixed on said shaft, of a fabricated compressor casing comprising a plurality of wall sections welded together to provide a rigid structure which defines an inlet, an impeller wall adjacent to one side of the impeller and a wall extending axially with respect to said impeller wall, lugs permanently fixed to said axially extending wall provided with finished surfaces dimensioned with respect to the inner surface of said impeller wall, detachable means fastening said lugs to said spaced supporting arms, and front and rear scroll sections attached to said rigid structure.

5. In a supercharger, the combination with a bearing housing having spaced supporting arms, a shaft, and an impeller fixed on said shaft, of a fabricated compressor casing comprising a plurality of wall sections welded together to provide a rigid structure which defines an inlet, an impeller wall adjacent to one side of the impeller and a wall extending axially with respect to said impeller wall, lugs permanently fixed to said axially extending wall provided with finished surfaces dimensioned with respect to the inner surface of said impeller wall, detachable means fastening said lugs to the bearing housing, front and rear scroll sections attached to said rigid structure, and supporting means for the supercharger comprising ears attached to the peripheral portion of the scroll section and reinforcing ribs between said ears and lugs.

6. A fabricated welded compressor casing structure comprising a plurality of walls of heavier pressed metal united by fused metal to form a rigid structure which provides a diffuser, a wall adjacent to which the compressor impeller runs and spaced mounting lugs having supporting surfaces accurately dimensioned with respect to the inner surface of the wall adjacent to which the impeller runs, and a plurality of walls of lighter pressed metal attached to said rigid structure to define a discharge scroll.

7. In a supercharger, the combination with a bearing housing having spaced supporting arms,

a shaft, and an impeller fixed on said shaft, of a fabricated compressor casing comprising a plurality of wall sections welded together to provide a rigid structure which defines an inlet, an impeller wall adjacent to one side of the impeller and a wall extending axially with respect to said impeller wall having a diameter greater than the impeller diameter, lugs welded to said axially extending wall having finished mounting surfaces spaced with respect to the inner surface of said impeller wall, bolts fastening said lugs to said spaced supporting arms, and front and rear scroll sections attached to said rigid structure.

8. In a compressor having a bearing housing, a shaft, and an impeller overhung on an end of the shaft, a fabricated compressor casing structure comprising a plurality of pressed metal parts united by fused metal to form an inlet, a wall adjacent to which the impeller runs, a diffuser which surrounds the impeller, an axially extending annular wall of a diameter larger than the impeller, and walls which define a discharge scroll, said structure being positioned around the impeller by passing the impeller through said axially extending wall, means for attaching said structure to the bearing housing, and a plate carried by the bearing housing for closing the opening through said axially extending wall.

9. In a centrifugal compressor, the combination with a shaft, an impeller on the shaft, a bearing for the shaft, and supporting members on bearing, of a fabricated compressor casing having a plurality of walls united by fused metal to provide a rigid structure comprising spaced walls which define a diffuser surrounding the impeller, a wall adjacent to which the impeller runs and an axially extending wall having mounting lugs provided with surfaces accurately spaced from the inner surface of the wall adjacent to which the impeller runs, means detachably connecting said surfaces to said supporting members, and walls forming a discharge scroll connected to said rigid structure.

10. In a supercharger, the combination with a bearing housing, a shaft and an impeller fixed on said shaft, of a fabricated compressor casing comprising a plurality of wall sections welded together to provide a rigid structure which defines an inlet, an impeller wall adjacent to one side of the impeller and a wall extending axially with respect to said impeller wall having a diameter greater than the impeller diameter, lugs carried by said axially extending wall having finished mounting surfaces accurately spaced with respect to the inner surface of said impeller wall, means fastening said lugs to the bearing housing, and walls defining a scroll attached to said rigid structure.

HOWARD A. JOHNSON.
